UNITED STATES PATENT OFFICE.

CHARLES C. MEUTSCH, OF BUFFALO, NEW YORK.

MATTRESS, CUSHION, AND SEAT.

Application filed February 24, 1920. Serial No. 360,936.

To all whom it may concern:

Be it known that I, CHARLES C. MEUTSCH, a citizen of the United States, and a resident of the city of Buffalo, in the county of Erie and State of New York, have invented certain new and useful Improvements in Mattresses, Cushions, and Seats, of which the following is a full, clear, and exact specification.

10 This invention relates to improvements in mattresses, cushions and seats constructed of a number of coiled springs and with pockets individually enclosing, permanently confining, and preventing adjacent springs from 15 contacting with each other in their operative position, which pockets have heretofore been made from strips of fabric folded lengthwise centrally of their width, with their folds secured together by parallel lines 20 of stitching passing therethrough at a right angle to their length at a predetermined distance apart for forming integrally closed connected pockets in series and open at one end for the insertion of a spring.

25 With all of the advantages possibly attributable to the construction of articles of manufacture above referred to, provided with spring containing pockets closely connected and in series from folded strips of 30 fabric, as above described, there still remains the objection that each spring must be inserted endwise, normally compressed against the closed end of its pocket, and so maintained, before it is possible to close the 35 open end of the pocket upon the spring by bringing its free edges together as must be, for locating and inserting therethrough a line of stitching usually employed for permanently closing the open end of the pocket 40 against the end of the strips.

Owing to the necessity of, and the skill and experience required for compressing and so maintaining the springs in their respective pockets for permanently closing their 45 open ends, manufacturers of these pockets before my invention have been compelled to permanently confine the springs in the pockets, and ship the assembled strips in compressed bundles for convenient handling, at 50 not only an objectionable expense, but frequently to the injury of the springs, if not the fabric of the pocket.

The prime object of this invention broadly stated is to secure the several advantages at-

tributable to the use in mattresses, cushions and seats, of pockets formed in series from a folded strip of fabric enclosing and confining coiled springs in their operative position against contact with each other, and in addition thereto, by the smallest possible change therein, secure all of the advantages derived from permanently closing the open ends of these pockets before the insertion of their springs; from the insertion of springs permanently to their operative position and against accidental detachment, and their removal therefrom quickly and with ease when injured for the substitution of other springs without the exercise of any special experience or skill on the part of the assembler, either a man or child as may be, and whereby the springs and pockets may be separately shipped to and assembled at their destination and at a minimum expense.

In the construction of mattresses, cushions and seats, with spring containing pocket strips, it is the common practice to arrange them in parallel rows with the springs directly opposing each other or else in staggered arrangement, and before my invention to closely connect the top coils of adjacent springs with clips, or else by means of twines or tapes extending longitudinally and transversely across the surface of the pockets, through, and around the corners of the pockets, and the top coils of the springs, leaving the coils intermediate the ends of the springs free to bend laterally in every direction.

When the top coils of the springs are so connected the force directly compressing any one or more springs is transmitted to all other springs and operates to laterally bend these other springs and tilt their top coils directly towards the compressed springs, with the result that these other springs are not only distorted, but that their tilted top coils exert a pressure against the occupant of the structure.

As the example in a seat structure, the occupant of less than the whole number of springs soon discovers that the other springs are exerting a force, which is not only uncomfortable, but tends to move him forwardly from his seated position, with the result that he either consciously or unconsciously inclines his body forwardly in efforts to ob-

tain relief, that is to say, changes the angle of his body from his natural seated position to an unnatural position because of the constant pressure of springs from every direction against the unseated portion of his body.

Furthermore, with the top coils of the springs so connected, with their remaining coils free to bend and move laterally, as has 10 been the common practice before my invention, the structure as a whole is not adapted to prevent the displacement of the springs from their normal position following the exposure of either its opposing side 15 or end edges respectively to a laterally compressive force, and as a result of which the structure is distorted in shape.

Another object of my invention therefore, is to provide in a structure composed of 20 closely connected springs in parallel rows, a means preventing the force compressing any one or more springs from being transmitted to others in such structure, and the lateral bending and tilting of any of the 25 springs, and which is further adapted for sustaining and maintaining every spring normally in its upright position, and against displacement tending to distort as a whole the shape of the structure.

30 With these ends in view, my invention finds its embodiment in certain feature of novelty in the construction, combination and arrangement of parts, by which the said objects and certain other objects are obtained, 35 as herein fully described with reference to the accompanying drawings and more particularly to the claims.

In said drawings:—

Fig. 1 is a perspective view of a mattress, 40 cushion or seat as may be, in which my invention finds its embodiment, with a part thereof broken away;

Fig. 2 is a side elevation of a series of 45 pocket strips, one of the pockets of which is slightly in perspective, of my invention;

Fig. 3 is a perspective of the pockets containing my invention with the springs located therein in their operative position;

Fig. 4 is a top plan view of a mattress, 50 cushion or seat structure showing the preferred arrangement of the lacing therefor;

Fig. 5 is a similar view showing a modified arrangement of the lacings; and

Fig. 6 is a similar view showing a further 55 modification in the arrangement of the lacings.

Similar characters of reference indicate the same parts in the several figures of the drawings.

60 In carrying out my invention I may, as heretofore, employ a strip of fabric folded upon itself at 8, with its free edges extending on a line parallel with the fold, and secured together by one or more transverse 65 lines of stitching 9, dividing the folded strip

into a series of closely connected pockets 10, the free ends of the meeting edges of the fabric of which are secured together by a line of stitching 11, permanently closing the pockets at their otherwise open ends, before 70 the insertion of their coiled springs 12.

In further carrying out my invention, every pocket is provided at one side lengthwise thereof, with an elongated slit 13 of sufficient length for inserting the coiled 75 springs 12 to their operative position in the pockets, which may be performed without any previous experience or skill, by compressing the springs between the thumb and fingers.

80 The ends of the slits 13 terminate inwardly from the closed ends of the pockets sufficiently to enable the surrounding sides of the pocket to confine the springs in their operative position against lateral movement and from accidental detachment.

The transverse lines of stitching 9 at the opposite sides of these pockets are preferably converged towards each other, and adjacent the fold as indicated at 14—14, and as is also 90 the line of stitching 11 securing the meeting edges of the fabric together to form outwardly projecting cone-shaped ends for the pockets, as a means for stretching them smoothly across the ends of the springs and 95 centering the springs in their operative position, as well as preventing lateral movement.

As shown in Fig. 2, the meeting edges of 100 the folded fabric may be cut away to form scallops, so that after stitching them together and turning the folded strip inside out, a neat inturned seam 15 will be formed in the absence of surplus material, possibly preventing the freedom of the contraction 105 and expansion of the springs in their pockets.

From the foregoing it will now be apparent that with but a small change in pockets heretofore formed from folded strips of fabric, my invention provides for the first 110 time a means by which it is possible and practical to dispense with the heretofore necessity for finally assembling the springs in their pockets at their place of manufacture before shipping them, for substantially 115 reducing the cost of their transportation; the liability of injury to the springs in transit, and a means avoiding the objections heretofore made by purchasers to shipping the springs and pockets separately, and being compelled to assemble them for use at 120 their destination.

In short, my invention provides for permanently closing both ends of the pockets at their place of manufacture; shipping them in closely packed bundles or bales, and with their spring in a very small compact bundle, so dense as to be substantially solid; accordingly convenient for handling in transit, and in a form best adapted to prevent 125 130

their being injured from any cause, at not more than a minimum expense for the packing and shipping charges therefor.

Referring now to that part of my invention for preventing the force directly compressing any one or more of the springs from being transmitted to and tilting other springs, it is here noted that my invention provides for the separation of the pockets in 10 the strips by two parallel rows of stitching 9—9, separated sufficiently for locating between them a slot 16 for the passage therethrough, about midway between the ends, of one or more fabric strips adapted for 15 maintaining the springs in their pockets in an upright position and against forces laterally thereto, tending to distort the shape of the construction in which they are used.

In Fig. 4, for example, two lacing strips 20 are preferably employed, one of which 18 is stitched at one end to the corner pocket 19, whence it extends through the slots 16 between the outer and adjacent row of pockets, around the pocket 20, between the inner row 21 adjacent thereto, and thence between the last mentioned row and the adjacent outer row thereto, partly around the corner pocket 22, to which it is secured, and which is located diagonally opposite the 30 pocket 19, surrounding the outer sides of the side and end rows of the structure.

Shown in Fig. 4 is another and similar lacing 24, the ends of which meet, and are stitched through the opposing end of the lacing 18 and to the pocket as indicated at 25.

As shown in Fig. 5, however, separate lacing strips 26 may be used between each 40 row, with their ends fastened respectively to the pockets at each end of the row and the several rows be surrounded by a lacing strip 27, the ends of which meet and are secured to the corner pocket 19, or, if preferred, to some one of the other three corner pockets.

45 As shown in Fig. 6, a single strip 28 may be used both for lacing the rows of and surrounding the pockets by passing the strip from the corner pocket 29 across the end and thence along the side of the structure, to and around the corner pocket 30, thence between the outer row and adjacent inner row, around the pocket 31 of the inner row, thence between the two inner rows and around the pocket 32, to and between said 55 rows and the outer row, around the pocket 29 to the pocket 30, and thereafter securing the ends of the strips by stitching 33 passing through the double thickness of strip to and through the pocket 29, and likewise securing the other end of the strip to the pocket 30 by stitching it therethrough, as indicated at 34.

Fig. 6 provides for lacing the several rows of pockets together by means of a single 60 strip, and Figs. 4 and 5 by means of two

or more strips, respectively securing substantially the same advantages due to the use of a single strip, and of using strips varying in length and reducing wastage accordingly, as might be if my invention were 70 confined to the use of a lacing consisting of a single strip.

As a means for preventing the sagging of the lengthwise folds in the lacing, as above described, the edges of the strip are knotted 75 (see Fig. 3) by short pieces of twine to the edges of the ends of the fabric between adjacent springs, as indicated at 35, and preferably at both ends, but need be only to about every third or fourth pocket, and as 80 indicated at Figs. 5 and 6, that part of the lacing enclosing the springs as a whole is secured at its top and bottom edges to the corners of the pockets adjacent thereto, and also if desired around the end coils of their 85 springs.

That portion of the lacing strip which surrounds the outside springs of the structure is preferably made slightly wider than the remaining portion and the other strips 90 passing between the several rows of springs, and yet so narrow that when tacked to the top and bottom edges of the pockets, the adjacent edges of the pockets will be drawn inwardly toward each other, as indicated 95 in the drawings, for permitting the strips to move to close contact with the edge of the outer covering for the springs, for producing a soft spring edge, and prevent the coils of the spring from working through 100 the cover.

The lacing strip and the strips passing between the rows of springs, as shown in the drawings, furnish a broad band preventing the coils between the ends of the springs from bending laterally; the coils of adjacent springs from passing between and interlocking with each other, and accordingly reducing their efficiency; dispense with any necessity for connecting the adjacent 105 end coils of the springs; maintain every spring free to respond to a force directly compressing it, without transmitting that force to any other springs either adjacent or remote therefrom, and thereby provide 110 for the use of springs confined in pockets in a structure comfortable to the occupant in every position his body may rest when either seated or lying thereon.

For quickly and accurately locating the 115 lines of stitching separating the pockets, for the scalloped edges thereof, and for the slits in and slots between the pockets, the strip of fabric from which they are to be formed is first marked off with a lead pencil accordingly, followed by piling the strips in a spread-out condition, one upon the other, and with either a chisel or a die cutting through the pile forming the slits and slots, and the serrated edges of the strip, 120 125 130

and all this, of course, before folding the strip upon itself and inserting the stitching along the marked lines.

Having described my invention, what I claim and desire to secure by Letters Patent is:—

1. A device for the purpose described comprising in combination parallel rows of fabric pockets, a spring for each pocket permanently enclosed therein, and a lacing separate from and extending lengthwise between the several rows of pockets, and connected at intervals to and adjacent the ends of said pockets.

15 2. A device for the purpose described comprising in combination a series of pockets arranged in parallel arrangement, a lacing strip of fabric separate therefrom, the width of which strip substantially corresponds with the length of the pockets, extending between and connecting together the several rows, a means for connecting the edges of said strip to and adjacent the ends of said pockets at intervals thereof, and 20 which provides for an outside band enclosing the structure formed by said single rows of pockets,

3. A device for the purpose described comprising in combination pockets formed in series from a folded strip of fabric, provided with parallel rows of stitching extending transversely thereof, and with a slot located between said parallel rows of stitching, and a separate lacing strip extending between said rows and passing through the slots of and around the several rows of pockets, which said strip is adapted to maintain the springs from bending laterally and form a binding strip surround-

ing and enclosing several rows of pockets, 40 and prevent the coils of adjacent springs from projecting between each other.

4. A device for the purpose described comprising in combination a series of integrally connected pockets formed from a folded strip of fabric, provided with parallel lines of stitching extending transversely of and connecting said folds, the connecting fabric between which pockets is provided with an elongated slot, a separate lacing strip laterally extending substantially the distance between the ends of said pockets, secured at its top and bottom edges to the fabric connecting the pockets, a coiled spring permanently enclosed in each of said pockets, which said lacing strip surrounds and encloses the several rows, and is stitched at its edges respectively to the pockets adjacent thereto towards the ends of said pockets.

5. A device for the purpose described comprising in combination a series of coiled springs, individual fabric pockets therefor, the closed ends of which are in the form of hollow cones projecting outwardly therefrom for centering the springs therefor, and whereby the tension of the coiled springs operates to stretch the fabric of the ends of the pockets across their ends and maintain the ends of said springs from lateral movement therein.

In witness whereof, I have hereunto set my hand and affixed my seal, this 4th day of February, A. D. 1920.
